FLAT COLOR CATHODE RAY TUBE
Henry Kasperowicz, Clifton, N.J.
(3 Greenvale Ave., Wayne, N.J.)
Filed June 21, 1963, Ser. No. 289,543
16 Claims. (Cl. 315—21)

This invention relates in general to a Cathode Ray Tube for displaying video images and is particularly directed to the flat type color cathode ray tube for displaying color or monochrome images.

In general cathode ray tubes and particularly those of the color type are generally arranged to have their target surfaces constructed with phosphor patterns arranged to receive electron beams at substantially high velocities and to produce color images therefrom corresponding to color information transmitted from a remote or proximate transmitting station. Color tubes of the flat variety, as a viewing device, have certain and definite advantages both economic and technical that make it superior to those types of the so-called conventional glass bulb type such as those commonly designated as the shadow mask color tube and the Lawrence color tube. The shadow mask tubes lack brightness and there are inherent difficulties in maintaining convergence and color registry because of the nature in which these tube types function and operate.

The Lawrence or Chromatron tube in particular uses what is termed a post deflection internal switching grid to produce its color images. Basically the grid is composed of a series of parallel vertical wires lying in a cylindrical plane. The grids in particular being two separate interleaved electrodes to which the switching voltages are applied. Patent No. 2,692,532 shows in some detail the details and principles of operation of this particular grid and tube structure. The quality of color registry, as will be apparent to those skilled in the electron-optic art, that this tube type will be capable of, will entirely depend upon a definite geometric relationship between the internal surface of the phosphor face panel of the tube and the curvature of the cylindrical grid. In reality the commercial television tube bulbs from which the tube is constructed, are not available, or are they manufactured with the necessary toroidal surface required to match the cylindrical switching grid and accordingly special tube bulbs have to be manufactured or molded to conform to the special configuration of the switching grids. The special molded toroidal bulbs are relatively expensive compared to the tube surfaces commercially available, so that the economics of producing the special bulbs become prohibitive and therefore they are noncompetitive with commercially available devices.

Now is the internal switching grid used in this tube type an inexpensive item to produce. If we consider such a color tube in a 21" diagonal size, there are approximately 1100 vertical, evenly spaced, parallel wires that are approximately tensioned to .4 lb. each and which need to be anchored to a substantially strong and heavy internal frame. The manufacturing costs of such a structure are relatively high and add to the cost of the already mentioned bulb cost.

There is presently available a flat cathode ray tube such as the one described in U.S. Patent No. 2,795,731. This tube has become further advanced and improved by inventions of Geer-Aiken, and called the Geer-Aiken color tube. This particular tube has none of the limitations or disadvantages inherent in those tubes previously mentioned. In particular this tube uses for its envelope either plate or tempered glass which may or may not be used in combination with a chrome-iron alloy. Such thin tubes are cheaper than those tubes utilizing the bulbs presently available. Further, so-called convergence difficulties are non-existent. The over-all beam focus char-

2

acteristics of the flat tube are superior to those of the shadow mask and Chromatron or the post deflection focusing (PDF) color cathode ray tubes.

In the Geer-Aiken color tube, three separate cathode-ray electron beams representing each of the primary colors, red, blue and green, are made to impinge a target surface in the tube in accordance with the electrostatic deflection principles as described in the U.S. Patent No. 2,795,731. Two of the beams in particular are made to impinge the target at a particular point on one surface and the other beam made to impinge simultaneously the same point location on the opposite surface of the target area. The three beams each impinge a different colored phosphor so as to produce in the aggregate a representative color image in accordance with the signal transmission. The type of target structure above described produces when impinged an effect that is commonly termed "Parallax." This is a form of visual distortion when viewing the impinging point from a position other than directly in front or normal to the surface. In other words, if one looks at a particular impinging point from the side, he will see a composite of two picture forms in two separate and distinct planes, so that unless the viewer is sitting directly in front of the picture and fairly well back, the inherent "Parallax" in the two-planer color presentation will appear as color mis-registry. Accordingly, as the viewing angle increases from the normal, the color mis-registry will appear to become greater. This condition will be most severe when viewing mono-chrome or black and white presentations. Under these conditions, small apparent mis-registrations which would be undetected in a color presentation would plainly stand out as color fringing.

Another limitation as relates to this particular target structure is an "onion-skin" effect. This effect can be best demonstrated by placing a thin translucent sheet of paper such as onion-skin in intimate contact with a photograph or some printed copy. The viewer will have little trouble with either seeing or reading the copy through the onion-skin. As soon as contact is destroyed, however minutely, resolution is destroyed. As the distance between the copy and the onion-skin is increased, any identification of a copy becomes an impossibility.

Transferring this principle to the phosphor screen target of the Geer-Aiken tube, it can readily be seen that both sides are, in effect, diffusion surfaces such as onion-skin paper, and this is due to the light-scattering properties of the phosphor particles affixed to both planes of the glass substrate which acts as the viewing surface. The degree of loss in resolution and also in color saturation will depend on the particle sizes of the phosphors as well as on the thickness of the viewing screen, i.e. the distance between both phosphor planes. Since the distance will always be finite in such a structure, this effect can never be completely or satisfactorily eliminated.

It is therefore one of the principal objects of the invention to produce an improved type cathode-ray tube.

Another object of the invention is to provide a flat type cathode-ray tube which eliminates "onion-skin" and "Parallax" effects.

Another object of the invention is to produce a cathode-ray tube which is more efficient, brighter, higher in resolution, and is more economical to manufacture and operate, and maintain.

Another object of the invention is to provide an improved type metalized target surface which can be readily and simply formed or molded and positioned within the said flat cathode-ray tube with no shrinkage or breakage generally encountered with glass target structures.

Another object of the invention is to provide a cathode-ray tube having no deflection yokes and circuitry there-

for and no convergence yokes and circuitry therefor and getting the same picture effects as though such yokes were present and functioning.

A still further object of the invention is to provide a cathode-ray tube requiring no specialized glass bulbs or surfaces necessary to conform to any of the target surfaces or electrodes within the standard types of tubes.

And still another object of the invention is to provide in a cathode-ray tube having three electron guns in a single plane to produce color and monochrome images a target structure which is impinged on only one surface and capable of being viewed from both sides of the said target structure, two of the said guns being directed towards each other.

Other objects and advantages will become apparent from a reading of the specifications and a study of the accompanying drawings and wherein:

FIGURES 1a and 1b show a simplified pictorial representation of the flat color tube according to the invention as embodied herein.

FIGURE 2, prior art, shows for informative purposes a target surface and the manner in which the electron beams impinge the said surface in a Geer-Aiken type color tube.

FIGURES 3a and 3b show for informative purposes three beams in a single plane and how they impinge the target surface in another plane according to the invention.

FIGURES 4a, 4b, and 4c show a target surface and a color phosphor pattern configuration thereon and the impinging beams according to the invention.

FIGURES 5a, 5b, and 5c show the target structure of FIGURES 4a, 4b, 4c, and an electron mask therefor for orienting and directing the electron beam relative to the target surface so as to permit the beams to impinge the proper phosphors according to the invention.

FIGURE 6 shows the electron mask assembly substantially magnified in part according to the invention.

FIGURE 7 shows the construction of the horizontal deflection plates and the manner in which the beam is directed to travel in a path parallel to the target screen before being again vertically deflected to ultimately impinge on the color screen target.

FIGURES 8a, 8b, and 8c show schematically the horizontal deflection plates and the manner in which the beams are made to undergo their transition from one direction to another at right angles thereto in accordance with deflection potential applied to the deflecting electrodes.

Now referring to the drawings and particularly to FIGURES 1a and 1b, there is shown schematically therein a flat color tube in which the color beams are all substantially in a single plane. In particular there is shown a color tube which operates on the deflection principles as taught in Patent No. 2,795,731 and comprises a color tube 1 having a target structure 2 upon which there is disposed a phosphor pattern or area 3. Target member 2 may be composed of glass or some other similar transparent member if the picture is to be viewed from the front surface. However, target member 2 may also be composed of a metal such as aluminum if the picture is to be viewed from the back. In the latter case the vertical deflection stripes or plates 2a are of a transparent and conductive material such as stannous oxide which is deposited on the back glass plate of the thin tube. Adjacent to the target area there is arranged a plurality of electron guns 5, 6, and 7; two of the guns 5 and 6 being at the lower portion of the target structure and arranged to have their respective beams traverse a path parallel to the base of the said target and in line with each other, and the third electron gun being at the top of the target structure and having a beam emanating therefrom traveling a path parallel to the upper portion of the target structure. The electron guns 5 and 6 inject along the bottom of the tube electron beams 8 and 9 each of which

5 pass over a row of horizontal deflection plates 10. Each of the respective horizontal plates are attached to a delay line 11 for receiving horizontal deflection voltages and are each at a fixed voltage suitable for producing the necessary electron fields. When the potential of one or more of these horizontal plates 10 is lowered below the normal operating voltage of the electrodes in the particular area, the horizontal traveling beam will be deflected perpendicular to its original path in an upward direction. Subsequent to this deflection, the beam then passes 10 through a transition region defined by cylindrical lens elements 12, the lenses controlling the width and shape and direction perpendicular to the plane of the tube as it is transferred from the low voltage horizontal deflection region to the high voltage region behind the phosphor. Once the beams reach the region behind the phosphor, it is redirected by a set of vertical deflection plates 14 normally operating at the same voltage as the phosphor screen. These plates in particular run horizontally and are further stacked one above the other on the back 15 wall of the tube. Here again, when one or more of the vertical deflection plates is reduced in voltage, the beam is again deflected, but this time at right angles to the initial bend and into the phosphor area or surface of the target. The manner in which the beams impact the target area is explained by the patent previously mentioned and is substantially accomplished by sequentially varying the voltage of the various deflection plates. Here again, 20 since all deflection is electro-static, relatively little power is required to perform the deflecting functions, although high voltages are involved.

25 By way of deviation and to better understand the workings of applicant's invention and its improvement over the prior art, there is shown in FIGURE 2 a typical illustration of the target surface in the Geer-Aiken tube previously referred to. In particular it will be noted that the target surface 20 has deposited thereon red and blue phosphor on its serrated or saw-tooth side and green phosphor on the opposite plane surface side. The electron guns 21, 22, and 23 are in two separate planes, the blue and red guns in one plane on the side of the target in which the blue and red phosphors are deposited and the other gun in a plane on the side of the target where the green phosphor is deposited. In the arrangement as shown the parallax and 30 and onionskin effect, as previously stated, become quite apparent.

35 To overcome these unwanted and objectionable effects, a target surface such as that shown in FIGURES 3a and 3b is proposed. In particular it may be observed that the three electron guns 25, 26, 27, representing respectively the blue, green and red beams, are all in a single plane in front of the target surface 28 so that no apparent parallax and/or onion-skin effect is noticed or evidenced. The deflection apparatus for producing the necessary deflection is not shown here but is comparable to the techniques described in the Aiken Patent No. 2,795,731. It can be appreciated from observing the target 28, and the manner of impingement thereof by the three color beams, 40 that the target area, and therefore the image displayed thereon, may be viewed from both sides of the target structure without getting the objectionable effects previously mentioned.

45 To obtain the necessary three phosphors, red, green and blue on a single surface 28 of FIGURES 3a, 3b, a novel arrangement of the phosphors as shown in FIGURES 4a, 4b and 4c is proposed as one embodiment of the invention herein. The said figures show a target structure 39 where FIGURE 4a is the plan view, FIGURE 4b the side or end view, and FIGURE 4c is the elevational view. The single plane arrangement of the three beams for impinging the target surface is as shown before with respect to FIGURE 3. In particular, the target structure 39 is substantially a rectangular ribbed shaped glassous or metallic relatively thin surface member upon 50 which are deposited the red, green and blue phosphors

upon one surface only. The horizontally ribbed shaped rectangular surface area 30 is arranged into a series of equal width vertical strips with alternate strips 32 having deposited thereon red phosphor and alternate vertical strips 33 adjacent thereto further horizontally subdivided into equal widths or blocks 34, 35, the said blocks having alternate green and blue phosphors deposited thereon. The geometric pattern of the primary phosphors as shown will in the aggregate produce white when the proper beams impinge thereon in accordance with well defined principles of color television.

Merely by way of instruction and illustration, the alternate red and blue/green stripes can be approximately .015" in width, which by the standards established in the Lawrence or Chromatron tube, is a pretty coarse stripe. However, their picture was formed of vertical stripes alone. In the proposed tube the mixing of the primary color by eye is achieved much more effectively because of the geometric phosphor arrangement, than that achieved by the above mentioned tube.

The vertical resolution will be determined by the saw-tooth pitch. A peak-to-peak distance of .025" or 40 pitch will give more than adequate color resolution in the vertical direction, and such dimensions are indeed easily attainable in the present invention.

As seen from the illustrative figures, the substrate or surface upon which the phosphor is deposited are saw-tooth planes. The phosphor substrate may be of glass, either molded or ground to the desired saw-tooth pitch. In this case, it would also serve as one of the windows in the vacuum envelope, enabling the picture to be viewed from either side of the color cathode-ray tube.

The target structure 30 may also be constructed from metal foil, such as aluminum, the phosphor being deposited upon the substrate thereof the same as on the glass structure. The use of an aluminum substrate would be relatively inexpensive since the material is relatively cheap and could be very easily stamped out to the desired configuration, pitch, shapes and etc., with no apparent change in the physical characteristics of the surface from one tube to the next, which would otherwise be the case where individual grinding would be necessary in the case of glass. The planes upon which the phosphors are to be deposited will be definite and more clearly defined and differentiated from those formed on glass by molding or pressing techniques. Another factor in the use of metal is that considerably more ridges or serrations may be defined per inch than glass, since in glass sharp differential planes would soon be lost by pressing or molding techniques as the saw-tooth pitch were increased. The material may be thin aluminum foil stamped and fixed in the manner stated above to the desired configuration, thereby having increased strength as a result of the said configuration, and thereafter having the appropriate phosphors deposited in a suitable manner, and then suitably mounting the stamped metal foil to a glass or metal back surface. Further, because of the metal's high reflectivity, the normal metalizing steps presently necessary in color tube manufacture, would thereby be eliminated, thus contributing to the efficiency of the phosphor screen.

In studying the phosphor arrangement as shown in FIGURES 4a, 4b and 4c, it is seen that essentially the primaries are arranged in vertical stripes, e.g. a blue/green stripe will alternate with a red stripe. It will also be seen that because of the trajectories that the blue and green beams follow under deflection conditions, they cannot but hit their respective colors in any blue/green stripe. The green phosphor, for instance, is so masked by ridged crests that it cannot be excited by the blue information carrying beam. In the same way, the blue phosphor cannot be activated by the green information carrying beam. However, from a close study of the respective beams, it is possible for both the blue

10
15

and green beams to activate the red stripes by over-extending themselves beyond the point of impingement of the respective blue and green phosphor positions these are supposed to hit. It is also possible for the red beam to impinge the green phosphor area by over-extending itself beyond the read phosphor area intended to be hit. Thus to eliminate these possibilities and to assure that the beams impinge only those areas necessary to obtain a true representation of the signal transmitted, what is necessary and proposed according to another embodiment of the invention, is the insertion of a mask proximate to the electron beam structure to assure appropriate orientation of the receptive beams to effect proper color fidelity.

15 The masking arrangement for assuring proper orientation of the color beams is shown in FIGURES 5a, 5b, and 5c, and further magnified by FIGURE 6. In particular the mask assembly 40 comprises a ladder type structure having a pair of elongated parallel spaced 20 apart support members 41, 42 extending in a direction parallel to the electron beams when they are in an undeflected state. In the description of the mask assembly, only the one controlling the red and green beams is shown, however, it being understood that a similar 25 mask is contemplated, but not shown, for the blue beam. Transverse to the elongated members 41, 42 and attached thereto are a plurality of equally spaced apart strips or baffle plates 43, each equal in width and thickness and preferably made of non-magnetic metal such 30 as non-magnetic stainless steel and the like. The width of the strips 43 will effectively depend on the size of the tube in general, on the degree of resolution desired in the horizontal direction and will approximate the width of either the red stripe or the blue/green stripe. Also the 35 width may vary since it will be a function of the strip's distance from the undeflected beam and the beam velocity. Further, the spacing between strips 43 will be approximately equal to its width.

40 In FIGURES 5a, 5b, 5c and 6 it may be seen that the center of the metallic strips 43 lies directly beneath the junction of the red and blue/green phosphor stripes. In other words, the metallic stripes are staggered in relation to the phosphor stripes. This particular arrangement confines the green and read electron beams to 45 their proper electron-optic path so that registry is assured. Hence the information carrying electrons from the green gun, as they are horizontally deflected, will be prevented from exciting the red stripes by the interception of the electron mask. In the same manner, electrons from the red gun will be unable to impinge upon the green squares. By adding a similar electron interceptor mask for the blue gun, and in registry with its green/red counterpart, we now have means of controlling color purity over the entire phosphor screen surface.

55 The flat tube arrangement presented herein lends itself to a unique type of deflection system particularly embodied in U.S. Patent No. 2,795,731 previously referred to. In this system the nature of the control zones and adjacency of the field defining and deflection elements presented to the electron beam is such that, for given operating field and deflection voltages, no substantial electrical limitation is presented as to the size of the image screen which may be scanned. Thus in the embodiment shown in FIGURES 7, 8a, 8b and 8c, the horizontal sweep deflection system is designed to operate at B+ voltage of the order of 1500 volts and the vertical sweep deflection system is designed to operate at a HV voltage of the order of 16 kv.; under the conditions, the dimensions of the viewing screen may be materially increased without necessitating a corresponding increase in HV and B+ values, the only limitation in such regard being acceptability of image intensity level. It will also be understood that the value of the necessary deflection voltages delivered to the respective horizontal and vertical sweep deflection elements likewise are not substantially

affected by the size of the image screen. Moreover, the arrangements presented are not restricted in size by beam deflection angle limitations inherent in cathode-ray tubes of conventional design. Hence beam scanning is here presented which does not require substantially increased accelerating voltages, increased deflection voltages nor increased depth to accomplish an increase in image screen dimensions. With the arrangements shown in the said figures, where the red and green beam velocity is 1500 volts, both beams will be in a field free zone when traversing those deflection plates at the same potential. However, when the beams enter those areas of lower potential the said beams will be deflected upwards accordingly. The electrical wave through the delay lines, as typically shown in FIGURE 1 will depress the deflection plate voltages in a typical scanning type process so that both the green and red beams will start to bend upwardly together. The beam as shown in FIGURE 7 can be made to bend in a smooth curve depending upon the gradation from the normal 1500 v. to the lower potential desired. Again this depends upon the deflection voltage wave form configuration through the delay lines. Figures 8a, 8b, and 8c show how the bending zone of the beams is changed with changes in the horizontal deflection plate voltage from the normal, 1500 v., to the zero or ground potential. The transition zone or lenses in which the green and red beams are first collimated and then accelerated to higher voltages would be above the point their bending first takes place. The deflection plates to which the deflection voltages are applied are shown as being channel shaped, but they may also be semi-circular, there being no definite preference as to configuration, since the effect will be the same.

The invention as disclosed is not to be limited to the specific drawing and description with respect thereto, but there are various changes and modifications which may be made, such as the pattern configuration of the color screen and the mask for achieving color purity may be altered without detracting from the invention herein. Another consideration to be given attention to is that the tube may be viewed from the back side, i.e. on the side that the electrons impinge on the screen in which case the light output becomes considerably greater than those color tubes previously mentioned since the efficiency of the phosphors are approximately three times higher on the side that the electrons impinge than they are on the normal viewing side.

Having described the invention, what is claimed, is:

1. A thin flat color cathode-ray tube having a deflection system for deflecting a plurality of coplanar beams each in a direction to cause them to impinge a target surface in the tube in a normal direction thereto at some definable position, the said thin flat tube comprising a target area having disposed thereon a geometric serrated phosphor pattern along one surface thereof to produce tri-colored images upon impact by the said coplanar beams as they traverse the said target area in accordance with the deflection system, and means in proximity to the target area for guiding the said beams in a direction to cause them to impinge the said phosphor pattern along one surface of the said target area at a location not inconsistent with the signal transmitted and to be reproduced.

2. A thin flat color cathode-ray tube having a deflection system for deflecting a plurality of coplanar beams each in a direction to cause them to impinge a target surface in the tube in a normal direction thereto at some definable position, the said thin flat tube comprising a target area having disposed thereon a geometric serrated phosphor color pattern along one surface thereof to produce tri-colored images upon impact by the said beams as they traverse the said target area in accordance with the deflection system, and means in proximity to the target area for guiding the said beams in a direction to cause them to impinge the said phosphor color pattern along one surface of the said target area at a location not inconsistent with the signal transmitted and to be reproduced.

3. A thin flat color cathode-ray tube having a deflection system for deflecting a plurality of coplanar beams each in a direction to cause them to impinge a target surface in the tube in a normal direction thereto at some definable position, the said thin flat tube comprising a glassaceous serrated target area having disposed transversely thereon a series of repetitive colored phosphor stripes along one surface thereof to produce colored images upon impact by the said beams as they traverse the said target area in accordance with the deflection system, and means in proximity to the target area for guiding the said beams in a direction to cause them to impinge the said phosphor color pattern along one surface of the said target area at a location not inconsistent with the signal transmitted and to be reproduced.

4. In a flat color type cathode-ray tube as in claim 3 and wherein said target area is metal.

5. A thin flat color cathode-ray tube having a deflection system for deflecting a plurality of coplanar beams each in a direction to cause them to impinge a target surface in the tube in a normal direction thereto at some definable position, the said thin flat tube comprising a glassaceous serrated target area having disposed transversely thereon a series of repetitive colored phosphor stripes along one surface thereof to produce colored images upon impact by the said beams as they traverse the said target area in accordance with the deflection system, and means including an electron mask in proximity to the target area for guiding the said beams in a direction to cause them to impinge the said phosphor color stripes along one surface of the said target area at a location not inconsistent with the signal transmitted and to be reproduced.

6. A thin flat color cathode-ray tube for reproducing transmitted picture signals and having a deflection system for deflecting a plurality of coplanar beams each in a direction to cause them to impinge a target surface in the tube in a normal direction thereto at some definable position, the said tube comprising a serrated tri-color target area having disposed transversely thereon a series of spaced repetitive red colored and alternate bi-colored phosphor stripes along one surface thereof to produce colored images upon impact by the said beams as they traverse the said target area in accordance with the deflection means, and means including non-magnetic perforated electron masks in proximity to the target surface for guiding the said beams in a direction to cause them to impinge the said phosphor color stripes at a location not inconsistent with the picture signal transmitted and to be reproduced.

7. In a flat color tube according to claim 6 and wherein in the said serrated target area is composed of glassaceous materials.

8. In a flat color tube according to claim 6 and wherein the said serrated target area is composed of a metallic material.

9. A thin flat color cathode-ray tube having a deflection system for deflecting a plurality of coplanar beams each in a direction to cause them to impinge a target surface in the tube in a normal direction thereto at some definable position, the said tube comprising a glassaceous serrated target area having disposed transversely thereon a series of repetitive colored phosphor stripes along one surface thereof consisting of alternate red stripes and alternate bi-colored blue/green stripes in between the alternate red stripes to produce colored images upon simultaneous impact by the said beams as they traverse the said target area in accordance with the reflection system, and perforated means for guiding the said beams in a direction to cause them to impinge the said phosphor color pattern at a location not inconsistent with the signal transmitted and to be reproduced.

10. A flat color type cathode-ray tube for reproducing picture signals comprising a target structure mounted therein, the said structure composed of a serrated area having colored phosphor stripes adhered thereto on one

surface in a repetitive pattern consisting of alternate red stripes transverse to the serrations and alternate stripes of bi-colored blue/green stripes between the red stripes, electron beam generating means in proximate relation to the target structure and disposed to transmit electron beams in a direction parallel to the horizontal edge of the target area and proximate thereto, beam deflection means adjacent to the target structure along the horizontal and vertical portions thereof and parallel thereto, and means including deflection voltage sources connected to the said beam deflection means for directing the said beams in a direction to cause them to impinge the phosphor pattern of the target structure.

11. A flat color type cathode-ray tube for reproducing picture signals comprising a target structure mounted therein and composed of a transparent serrated area having colored phosphor stripes adhered thereto on one surface in a repetitive pattern consisting of alternate red stripes transverse to the serrations and alternate stripes of bi-colored blue/green stripes between the red stripes, electron beam generating means in proximate relation to the target structure and disposed to transmit electron beams in a direction parallel to the horizontal edge of the target area and proximate thereto, beam deflection means adjacent to the target structure along the horizontal and vertical portion thereof and parallel thereto, and means including deflection voltage sources connected to the said beam deflection means for directing the said beams in a direction to cause them to impinge the phosphor pattern of the target structure according to the picture signals transmitted.

12. A flat color type cathode-ray tube according to claim 11 and wherein the beam generating means includes electron guns disposed in proximate relation to the horizontal extremity of the target structure, at least a pair of said electron guns being axially aligned so as to have their respective beams on a collision course.

13. A flat color type cathode-ray tube according to claim 11 and wherein the beam deflection means includes delay lines for receiving the deflection voltage sources.

14. A flat color cathode-ray tube for reproducing picture signals comprising a tri-color target structure mounted therein and composed of a metalized serrated area with colored phosphor stripes adhered thereto on one surface in a repetitive pattern consisting of alternate red stripes transverse to the serrations and alternate stripes of bi-colored blue/green stripes between the red stripes, electron beam generating means in proximate relation to the target structure and disposed to transmit electron beams in a direction parallel to the horizontal extremities of the target area and proximate thereto, beam deflection means adjacent to the target structure along the horizontal and vertical portions thereof and parallel thereto,

means including deflection voltage sources connected to the said beam deflection means for causing the said beams to scan the phosphor pattern of the target structure in a horizontal and vertical direction and perforated electron mask means in proximity to the beam deflection means for directing the colored beams to their corresponding colored phosphor on the target area.

15. A flat color cathode-ray tube for reproducing picture signals comprising a target structure mounted therein and composed of a serrated metalized area with colored phosphor stripes adhered thereto on one surface in a repetitive pattern consisting of alternate stripes of one colored phosphor transverse to the serrations and alternate stripes of bi-colored phosphor stripes between the stripes of the one colored phosphor, electron beam generating means in proximate relation to the target structure and disposed to transmit electron beams in a direction parallel to the horizontal edge of the target area and proximate thereto, beam deflection means adjacent to the target structure along the horizontal and vertical portion thereof and parallel thereto, and means including deflection voltage sources connected to the said beam deflection means for directing the said beams in a direction to cause them to impinge the phosphor pattern of the target structure.

16. A thin flat color cathode-ray tube having a deflection system for deflecting a plurality of co-planer beams each in a direction to cause them to impinge a target surface in the tube in a normal direction thereto at some definable position, the said thin flat tube comprising a glassous serrated target area having disposed transversely thereon a series of repetitive colored phosphor stripes along one surface thereof to produce colored images upon impact by the said beams as they traverse the said target area in accordance with the deflection system, and electron mask means composed of a channel ladder type member having a plurality of spacial transverse bars each having a width comparable to the phosphor stripes, the said mask being in proximity to the target area for guiding the said beams in a direction to cause them to impinge the phosphor stripes along one surface of the target area at a location not inconsistent with the signal transmitted and to be reproduced.
